UNITED STATES PATENT OFFICE

WILLIAM D. COLLINS, OF EVANSVILLE, INDIANA, ASSIGNOR TO SERVEL, INC., OF NEW YORK, N. Y., A CORPORATION OF DELAWARE

REFRIGERATOR CABINET CONSTRUCTION

Application filed July 27, 1928. Serial No. 295,701.

My invention relates to the art of refrigeration and particularly to that phase of the art having to do with the construction of refrigerator cabinets, and still more particularly to those adapted for mechanical refrigeration.

In my invention is embodied a new and novel manner of so constructing cabinets of this type that a minimum number of parts are required and the labor involved in their assembly is materially reduced.

Briefly, my invention contemplates forming a frame comprising upright and horizontal members lying in a single plane and suitably securing thereto a box-like metal liner having one open side. Suitable insulating material is placed around the five remaining sides of the liner and retained tightly in place by metallic bands. This assembly is then placed and suitably secured within an outer shell which is provided with a door for closing the open side of the liner. Due to the reduction in the amount of materials and labor required such a cabinet may 28 be manufactured at a much lower cost than has heretofore been possible.

Furthermore my improved construction prevents condensation of moisture adjacent the liner. If the insulation of a refrigerator cabinet is not tight against the liner and air can get in between the insulation and the liner, moisture precipitates due to the low temperature prevailing. This condensation must be guarded against, particularly with 35 mechanical refrigerator units, both to prevent water falling on the floor and to prevent rotting of insulation. By impregnating and coating the insulation with a suitable water proofing material of semi-viscous 40 character and strapping the insulation tightly around the liner, I am able to prevent air pockets next to the liner and avoid condensation of moisture.

My invention is fully pointed out in the 45 following description taken in connection with the accompanying drawings and further objects and advantages will be apparent therein.

Fig. 1 is a side view, partially in cross- 50 section of a cabinet constructed in accord-

ance with a preferred embodiment of my invention;

Fig. 2 is a front elevational view of the cabinet shown in Fig. 1;

Fig. 3 is a cross-sectional view taken on 55 the line 3—3 of Fig. 1;

Fig. 4 is a front elevational view of the interior assembly before being placed within the outer shell;

Fig. 5 is a side elevational view of the 60 assembly shown in Fig. 4;

Fig. 6 is a top elevational view of the assembly shown in Figs. 4 and 5;

Fig. 7 is a view, partially in cross-section, of some of the members which constitute the 65 interior assembly prior to being secured together.

The interior assembly as shown in Figs. 4 through 7 will first be described. The assembly, in its preferred form, comprises two 70 upright members 10 secured together by two horizontal members 11 and 12. Members 10 and 11 and 12 are preferably of wood and constitute a frame which lies in a single vertical plane. Member 11 is connected to members 10 at the top while member 12 is connected to them at a point some distance above the bottom.

Securely attached to this frame by means of screws 13 is a liner 14. Liner 14 is box- 80 shaped and has closed sides, top, bottom and back but an open front. The interior of the liner itself is preferably lined with porcelain fused thereonto. Around the five closed sides of the liner is placed a suitable heat 85 insulating material 15 such as cork board impregnated with water proofing fluid material such as hydrolene. The cork board may be in one single layer as is shown in Figs. 3 and 7 or two or more layers may be employed. In case a plurality of layers are used, the transverse joints in adjacent layers should be staggered so that there will be no joint extending all the way through the insulation at any one place.

On the outside of the insulating material 95 may be placed one or more layers of water proof paper (not shown). At the top, bottom and rear edges of insulation outside of the water proof paper are placed protective 100

angle pieces 16. These angle pieces do not necessarily extend the entire length of their respective edges. Two or more metal bands 17 are secured to horizontal member 11, pass 5 across the top of the insulated liner, down the back and underneath the bottom and are secured to lower horizontal member 12. A similar set of bands 18 pass around the sides and back of the insulated liner and have their 10 end secured to upright members 10. Still another set of bands 19 passes entirely around the insulated liner extending across the top, down one side, across the bottom and up the other side. The opposite ends of bands 19 are 15 joined together as shown at 20 thus forming what may be termed endless bands. Thus it is seen that the bands 17, 18 and 19 may be made to hold the insulating material tightly in contact with liner 14 while bands 17 and 18 20 also aid in securing the insulated liner to the frame. The pressure of the bands on the corner of the insulating material 15 is first applied to the protective angle pieces 16 which distribute the pressure evenly along 25 the respective edges.

An aperture is provided in the bottom of liner 14 and adjacent insulation through which extends a short length of drain pipe 21. An aperture may be cut in the back of 30 the cabinet for the passage of conduits for conducting refrigerant fluid to and from an evaporator.

The parts and their relationship thus far described constitute the inner assembly which 35 is placed within an outer shell 22. Shell 22 is preferably made of sheet metal suitably coated so as to resist rust and corrosion. Wooden members 23 are bolted to the bottom of the shell and serve to support the upright 40 members 10 which are secured thereto by means of angle brackets 24.

The front of shell 22 is formed so as to be in contact with two sides of members 10 and is secured thereto with the aid of a moulding 45 36.

Two or more brackets 25 are welded or otherwise secured to the inside of the back of shell 22 in such a position as to support the rear of the inner assembly.

50 The top and back of shell 22 are removable so as to permit the inner assembly to be put in place. The back is shown as being secured to the remainder of the shell by screws 37 which engage screw threads formed in angles 55 38 which are fastened, as by welding, to the side members of the shell. A similar type of construction may be used to secure the top to the main part of shell 22.

The front of shell 22 is provided with a 60 large upper opening and a smaller lower opening. The upper opening coincides with the open front of liner 14 and is normally closed by a door 26. Door 26 comprises a rectangular frame 27, preferably of wood, to which 65 is secured metal sheets 28 and 29. The space

between sheets 28 and 29 is filled with insulating material 15. A moulding 30 is placed around the inner periphery of door 26 and serves to cover the edges of sheet 28. The edges of sheet 29 are bent around the sides of frame 27 as is clearly shown at 31. Door 26 is hung on a pair of hinges 32 and is held in its closed position by a latch 33. An additional strip of wood 36 is preferably placed adjacent to frame 27 on the right hand side of the door as viewed in Fig. 3 in order to give additional support for the hinges. 70

The space within liner 14 may be termed a food storage compartment while the space in the lower part of shell 22 below the insulated liner may be aptly called the apparatus compartment. In the latter compartment is housed the apparatus comprising a mechanical refrigerating unit, with the exception of the evaporator which is placed in the food storage compartment. Access may be had to the apparatus compartment by means of a removable panel 34 which is provided with louvres 35 to allow circulation of air in case the refrigerating apparatus is of the air cooled type. Openings (not shown) are also provided in the back of the apparatus compartment to aid in the air circulation. 80

The preferred form of procedure in assembling the cabinet, made possible by its simplified construction, is as follows:

The wood frame is first constructed by securing together members 10 and 11 and 12. Liner 14 is then fastened to this frame. Next the cork board 15, impregnated and coated with hydrolene, is put in place around the outside of the liner and covered with water proof paper. Bands 18, 19 and 20 are then placed around the now insulated liner and put under sufficient tension to hold insulation 15 and the water proof paper firmly in contact with the liner. 100

The inner assembly is now slipped into place within shell 22, the back and top of the latter not yet having been placed thereon. Brackets 24 are secured to members 10 and 23 and the front of shell 22 is fastened to members 10 by means of moulding 36. The assembling of the refrigerator cabinet is now complete except for hanging door 26 and placing the back and top on shell 22. 105

The interior of the food storage compartment is provided with suitable supports for shelves which have not been shown as shelf arrangements are old and well known. 110

While I have shown and described a more or less specific form of my invention, it is to be understood that modifications thereof fall within its scope. For instance, the bands need not be all parallel or at right angles to each other but may pass around the insulated liner in any desired directions so as to secure the best binding of the insulation to the liner, though the arrangement shown is preferred. It will be understood that the in- 115 120 125 130

vention is to be limited only by the appended claims considered in connection with the prior art.

What I claim is:

- 5 1. A refrigerator cabinet comprising an inner assembly and a detachable casing for said inner assembly, said inner assembly comprising a front supporting frame, a liner having an open side, means securing said liner to said front frame with its open side adjacent the frame, and insulating material for the liner, said insulating material being secured to the liner and front supporting frame by said means. 70
- 10 2. A refrigerator cabinet comprising a front supporting frame, a liner having an open front secured to said front frame, insulation for the liner, securing means attached to the front frame and fastening said insulation to the liner and front supporting frame, an outer shell forming a casing for said liner, and means for detachably securing said outer shell in position. 75
- 15 3. A cabinet comprising an inner assembly and a detachable outer shell forming a casing for said inner assembly, said inner assembly comprising a front supporting frame, a liner having an open side, said liner being secured to said front frame with the open side adjacent the front frame, insulating material for said liner, and means attached to the front frame and securing said insulation to the liner and front supporting frame and securing the liner to the front frame. 80
- 20 4. A refrigerator cabinet comprising a front frame, a liner having an open side, said liner being disposed with its open side adjacent the front frame, insulating material for the liner, and securing bands having their ends attached to the frame and extending around said liner and insulating material, and holding the insulating material in position and the liner and front frame together. 85
- 25 5. A refrigerator cabinet comprising a front frame, a liner having an open side, said liner being disposed with its open side adjacent the front frame, insulating material for the liner, securing bands having their ends attached to the frame and extending around said liner and insulating material and holding the insulating material in position and the liner and front frame together, and a detachable outer shell forming a casing for said liner. 90
- 30 6. A refrigerator cabinet comprising a front frame, a liner having an open side, said liner being disposed with its open side adjacent the front frame, insulating material for the liner, securing bands having their ends attached to the frame and extending around said liner and insulating material and holding the insulating material in position and the liner and front frame together, and protective members between said bands and the insulating material at the corners. 95
- 35 7. A refrigerator cabinet comprising an inner assembly and a detachable casing for said inner assembly, said inner assembly comprising a front supporting frame, a liner having an open side, means securing said liner to said front frame with its open side adjacent the frame, insulating material for the liner, said insulating material being secured to the liner and front supporting frame by said means, and a door forming part of the casing and forming a closure member for the open side of said liner. 100
- 40 8. A refrigerator cabinet comprising an inner assembly and a detachable casing for said inner assembly, said inner assembly comprising a front frame, a liner having an open front disposed in contact with the front frame, insulating material for the liner, securing bands extending around the liner and holding the insulating material to the liner, certain of said bands having their ends attached to the front frame for securing the liner and insulating material to the front frame, and a detachable outer shell forming a casing for said liner. 105
- 45 In testimony whereof I have affixed my signature.
